UNITED STATES PATENT OFFICE.

ALEXANDER HARLAND VANNAUKER, OF HAZLETON, PENNSYLVANIA.

DYNAMITE-HEATER.

No. 911,463.

Specification of Letters Patent.

Patented Feb. 2, 1909.

Application filed November 1, 1907. Serial No. 400,269.

To all whom it may concern:

Be it known that I, ALEXANDER HARLAND VANNAUKER, a citizen of the United States, residing at Hazleton, in the county of Luzerne and State of Pennsylvania, have invented a new and useful Dynamite-Heater, of which the following is a specification.

This invention relates to dynamite heaters and has for its object to provide a comparatively simple and inexpensive device of this character in which the heating chamber is maintained at a uniform temperature thereby to prevent over-heating of the dynamite, or other explosive.

15 A further object of the invention is to provide a heater in which the lamp or other heating medium is protected from drafts so as to prevent the flame from being extinguished.

20 A further object is to provide improved means for locking the lamp within the heating chamber, and means for ventilating the latter.

25 A still further object of the invention is generally to improve this class of devices so as to increase their utility, durability and efficiency.

30 Further objects and advantages will appear in the following description, it being understood that various changes in form, proportions and minor details of construction may be resorted to within the scope of the appended claim.

35 In the accompanying drawings forming a part of this specification: Figure 1 is a side elevation of a dynamite heater constructed in accordance with my invention. Fig. 2 is a vertical sectional view of the same. Fig. 3 is a transverse sectional view taken on the line 3—3 of Fig. 2. Fig. 4 is a side elevation 40 of the lamp detached.

Similar numerals of reference indicate corresponding parts in all of the figures of the drawings.

45 The improved heater forming the subject matter of the present invention comprises a casing 5 preferably cylindrical in shape, as shown, and provided with a conical extension 6 terminating in a depending flange 7, the walls of the flange being extended laterally to form an annular reinforcing bead 8.

50 Disposed within the casing 5 above the combustion chamber 9 is a boiler 10 and arranged within the boiler is a substantially cylindrical receptacle 11 adapted to receive 55 the dynamite to be heated.

Extending laterally from the exterior walls of the boiler 10 is an annular flange 12 preferably L shaped in cross section and adapted to form a closure for the upper portion of the heating chamber 9, there being a similar flange 13 extending laterally from the exterior walls of the receptacle 11 and constituting a closure for the upper end of the boiler.

The flanges 12 and 13 are provided with oppositely disposed bayonet slots 14 which engage suitable locking pins or lugs 15 secured to the exterior walls of the casing and boiler, respectively, thereby to lock the boiler and dynamite receptacle within the casing.

70 Riveted, bolted or otherwise rigidly secured to the exterior walls of the casing 5 at the conical portion 6 thereof are spaced depending legs 16 having their lower ends deflected laterally at 17 and adapted to support the lower end of the casing in elevated position above the ground.

75 The legs 16 are reinforced and strengthened by the provision of an annulus or ring 18 which engages the legs 16 at the deflected portion 17 thereof so as to maintain said legs in spaced relation to each other and also in spaced relation to the depending flange 7 of the cylindrical casing.

80 Arranged within the heating chamber 9 is a conical shaped receptacle or reservoir 19 adapted to contain coal oil or other fuel, which latter is supplied to the wick 20 for heating the boiler 10.

85 The adjacent walls of the reservoir 19 are extended to form a depending flange 20' the marginal edge of which is bent laterally to form an annular reinforcing bead 21 adapted to bear against the reinforcing bead 8 of the flange 7 thereby to limit the upward movement of the receptacle 19.

90 Extending inwardly from the interior walls of the flange 7 is an annular rib 22 provided on its upper face with a flat shoulder for engagement with spring locking members 24 carried by the reservoir 19.

100 The locking members 24 are preferably in the form of flat springs each having one end thereof riveted or otherwise secured to the exterior walls of the reservoir while the opposite or free ends of the springs are spaced laterally from the reservoir to form offset portions for engagement with the shoulder of the rib 22, the terminal portions 105 of the springs being extended through open- 110

ings 24' in the skirt of the reservoir and thence extended downwardly beneath said reservoir to form finger pieces 25'.

It will thus be seen that by pressing inwardly on the finger pieces 25' the offset portions of the locking members will be forced in contact with the exterior walls of the reservoir so as to permit the latter to be readily positioned within the flange 7 of the casing. When the finger pieces are released the offset portions of the locking members will spring outwardly in engagement with the rib 22 and thereby lock the lamp against accidental displacement.

15 The walls of the flange 7 are formed with a plurality of perforations 26 which permit the passage of air to a chamber 27 formed between the flange and reservoir and thence to the combustion chamber 9.

20 By having the perforations 26 formed in the flange 7 the flame is effectually protected from side drafts so as to prevent said flame from being accidentally extinguished, it being here noted that the air entering 25 through the apertures 26 will come in contact with the inclined walls of the reservoir 19 and thence be deflected upwardly within the heating chamber 9.

20 By ventilating the lower end of the heating chamber in this manner the flame is kept in constant contact with the exterior walls of the boiler so as to maintain the water in said boiler at a uniform temperature and thus prevent over-heating of the dynamite or 25 other explosive within the receptacle 10.

While it is preferred to make the casing

and containing receptacles cylindrical in shape, as shown, it is obvious that the same may be rectangular in cross section or of any other angular formation without departing from the spirit of the invention.

Having thus described the invention what is claimed is:

A device of the class described comprising a casing having a conical extension and provided with a perforated flange, the terminal edge of which is bent to produce a reinforcing bead, supporting legs secured to the exterior walls of the casing and spaced from the flange, a lamp having inclined side walls 50 extended below the bottom of the same and provided with a laterally curved reinforcing bead adapted to engage the bead on the flange of the casing, said flange being provided with an annular rib extending inwardly 55 from the interior walls thereof and having an inclined face, and spring locking members secured to the inclined walls of the lamp and having their intermediate portions offset for engagement with the annular rib, the free 60 ends of the locking members being extended through recesses in the walls of the lamp and thence bent downwardly to form terminal depending finger pieces.

In testimony that I claim the foregoing as 65 my own, I have hereto affixed my signature in the presence of two witnesses.

ALEXANDER HARLAND VANNAUER.
